UNITED STATES PATENT OFFICE

123,710

DESIGN FOR A BROOCH OR SIMILAR ARTICLE

Jerome Berenzweig, Chicago, Ill.

Application October 16, 1940, Serial No. 95,878

Term of patent 3½ years

To all whom it may concern:

Be it known that I, Jerome Berenzweig, a citizen of the United States, residing at Chicago, in the county of Cook and State of Illinois, have invented a new, original, and ornamental Design for a Brooch or Similar Article, of which the following is a specification, reference being had to the accompanying drawing, forming a part thereof.

In the drawing,

Fig. 1 is a front elevational view of a brooch showing my new design; and

Fig. 2 is an edge view thereof.

I claim:

The ornamental design for a brooch or similar article, substantially as shown.

JEROME BERENZWEIG.
